Inventor:

Otto Lundell

By Wilson & Mc Cana

Atty's.

UNITED STATES PATENT OFFICE.

OTTO LUNDELL, OF ROCKFORD, ILLINOIS.

HEAT CONSERVER AND DISPENSER.

Application filed November 23, 1925. Serial No. 70,886.

This invention relates in general to heating appliances and more particularly to a heat conserver and dispenser to operate in conjunction with a suitable source of heat for economizing in the distribution of the heat from the source and for making such distribution moderate.

While the invention broadly comprehends its use for the economical and comfortable heating of dwellings and other places where permanent installations of the equipment may be made, it will suffice in the present description to refer to one particular embodiment of the invention where the general principle involved is shown applied to a small, portable heater unit for occasional use.

In the accompanying drawing illustrating the invention,

Fig. 1 is a vertical, longitudinal section through a heat conserving and dispensing device shown placed on an electric plate or other suitable heating source;

Fig. 2 is a perspective view of my improved device.

The present embodiment of my invention comprises a box-like container 5 of metal or any suitable material which is open at opposite ends and receives a heat absorbing body 6. The body 6 consists of a zigzag strip of sheet metal bent, as shown at 7 and 8 with the contiguous plates or laminæ 9 closely spaced and in mutually divergent and convergent relation. The bends 7 and 8 are transverse with relation to the open ends of the box, as illustrated, with the bends 7 flush with the end of the box at the bottom open end 10 thereof. This brings these points of the absorbing body 6 in intimate contact with the heating source 11 which, as stated above, is an electric plate but may be any other suitable or convenient heating element. The bends 8 protrude slightly from the open top of the box, as illustrated, thereby leaving draft openings 45 or vents 12 at opposite sides of the box. The opposite ends of the zigzag strip are bent as shown at 13 to overlie the upper edges of the box and support the body 6 therein.

The unit illustrated is merely for the purposes of the present description to convey a general understanding of the invention

and the principle involved. Consequently, it should be understood that no limitation as to size or the thicknesses of the parts is intended to be conveyed. In the use of the device, the same may be permanently attached over an electric plate by lugs 14 on a base 15 or the same may be removable for use wherever desired. In operation, the heat absorbing and storage body 6 can be heated up in the course of a few seconds depending on the size of the unit in hand and on the thickness of the metal used. After removal from the heating source or by shutting off the current supplied to the electric plate, in the present case, the body 6 will be found to hold heat for a considerable time, the heat dispensed being moderate and comfortable and not intense and local as in the case of portable heaters commonly used. The laminæ 9 reflect and radiate heat from one to another due to their arrangement and close relation and because of the fact that direct draft is kept therefrom by the box 5 serving as a shield therefor. The heating of the body from the source occurs rapidly by virtue of the direct conduction resulting from contact with the source at the bends 7. The dispensing of the heat is of course by radiation in which the vents 12 permit of the dispensing of heat from within the container from the spaces otherwise closed by the zigzag strip. There is, of course, a considerable saving in expense by utilizing my invention and I contemplate its use where the source of heat may be in intermittent operation for which purposes electrical appliances are, of course, most suitable. In this connection, thermostatic temperature controlling means may be used for closing and opening the circuit for the electric heating unit.

I claim:

1. In a heat conserver and dispenser, a box-like container having a heat outlet opening, and a heat absorbing body consisting of a zigzag strip of sheet metal placed inside the box with the planes of the bends therein transverse to the heat opening, the bends at said opening having draft openings, and the other bends being in intimate heat-receiving relation to a heating source.

2. In a device of the character described, a container providing a heat outlet opening, a heat absorbing body in said container consisting of a zigzag thin-walled radiating element having bends arranged transversely with respect to the aforesaid opening, and heating means disposed in juxtaposition to

the other bends to transfer heat to the radiating element, the first mentioned bends in said radiator element being open to the atmosphere at the ends thereof. ¹⁰

In witness of the foregoing I affix my signature.

OTTO LUNDELL.
